UNITED STATES PATENT OFFICE.

GEORGE F. GRUBE, OF EVANSTON, ILLINOIS, ASSIGNOR TO THE BELBER TRUNK & BAG COMPANY, OF PHILADELPHIA, PENNSYLVANIA, A CORPORATION OF PENNSYLVANIA.

WARDROBE TRUNK.

1,411,694.

Specification of Letters Patent.

Patented Apr. 4, 1922.

Application filed January 27, 1919. Serial No. 273,213.

To all whom it may concern:

Be it known that I, GEORGE F. GRUBE, a citizen of the United States, residing at Evanston, county of Cook, and State of Illinois, have invented a new and useful Improvement in Wardrobe Trunks, of which the following is a full, clear, and exact description, reference being had to the accompanying drawings, which form a part of this specification.

The object of my invention is to provide a device for use in wardrobe trunks by means of which the garments suspended in the trunk compartment may be held in substantially fixed position therein.

I am aware that this purpose has been heretofore accomplished by means of a retainer secured at the rear of the trunk compartment and adapted to extend over and in front of garments suspended from the garment supporter within the compartment and to be removably attached, at its lower end, to holding means secured along the inner side walls of the compartment and, at its upper end, to be either fixedly, adjustably or removably attached to similarly secured holding means. Such a structure is set forth in the Hawley Patent No. 1,258,566, dated March 5, 1918. The Hawley retainer has the advantage of elasticity, to secure which, however, it comprises a plurality of elastic strips spaced apart.

One of my objects is to provide a retainer which will be sufficiently elastic and yet present a continuous surface so that, when operatively positioned, it will cover and conceal the suspended garments or at least that portion thereof in front of which the retainer extends. Another object is to secure elasticity without resorting to the use of elastic material to form the body of the retainer, thereby substantially increasing its durability. Another object is to avoid the provision of special means, secured to the trunk wall, for holding the upper end of the retainer, but yet render the retainer readily removable from the trunk and as readily replaceable.

The invention comprises structural features adapted to effect these objects and also possessing other advantages from the standpoints of functional utility and economy of manufacture.

A preferred embodiment of the invention is shown in the accompanying drawings, 55 wherein—

Fig. 1 is a perspective view of a trunk with my improved garment retainer positioned in one of the compartments.

Fig. 2 is a front view of the garment retainer detached from the trunk.

Fig. 3 is a vertical sectional view of the retainer.

Fig. 4 is a horizontal section through the trunk above the level of the garment supporter.

a and *b* are the two hinged sections or compartments of the trunk. Section *b* has a hinged top *a* and is provided with a garment supporter comprising rods *e*, secured 70 to the rear wall of the compartment and projecting forward therefrom and supported at the front by angle bars *d*, and sleeve *f* in telescopic relation with rods *e* and slotted along their bottoms to permit them to slide 75 relatively to the angle bars *d*. By moving the sleeves *f* outward upon rods *e*, the length of the supporter may be materially increased as indicated in Fig. 4.

On the supporter is adapted to be suspended any number of garment hangers *g*, which may be of any conventional form. Hangers *g* may be slid back and forth along the supporter and may be individually lifted off and replaced.

The rods *e* are provided with holes *i* extending diametrically therethrough from top to bottom. The sleeves *f* are provided with holes *j* along their top surfaces. Holes *i* and holes *j* are equally spaced apart and 90 when the sleeves *f* are pushed back to their limit the two sets of holes *i* and *j* align.

In addition to the usual garment hangers *g* a hanger *h* is provided which may be of the same construction as the hangers *g* except that it is provided with downwardly projecting pins *k* adapted to engage the alining holes *i* and *j*. While the hanger *h* is removable and replaceable, like hangers *g*, it cannot slide along the supporter. 100

Suspended from hanger *h* is a retainer, the main body of which is a piece of cloth or canvas *m* having at the bottom the bifurcated extensions *n*, *n*, of similar material. Secured between the bifurcations, just below 105 the body *m*, is a cross-bar *o*, from which de-

pend a number of coil springs *p*. A cross-bar *r* is suspended from springs *p*. The cross-bar *r*, by means of ears *s*, carries a cross-rod *t* having end heads *u*.

5 Extending along opposite side walls of the compartment are angle bars *v* provided with notches *w* adapted to receive the ends of the rod *t*.

After the garments are suspended from 10 hangers *g* and the latter placed on the supporter *e*, *f*, the hangers are pushed back and the sleeves *f* are moved rearward on the rods *e*. The hanger *h* is then placed in 15 position in front of the hangers *g* and the pins *k* are engaged with the most rearward of the exposed holes *i* and *j*, thereby holding the hanger *h* in fixed relation with the supporter and preventing the hangers *g* from sliding forward on the supporter. The 20 lower cross-bar *r* is now grasped with the hand and pulled down in front of the notched angle bars *v*, until the rod *t* is below the front ends of these bars *v*, this extension of the retainer being permitted by the 25 extension of the springs *p*. The bar *r* is then pushed back as far as it is permitted to go by reason of the suspended garments, and the rod *t* is engaged with the notched angle bars *v*. By relaxing the pull on the retainer, 30 the springs *p* seat the rod *t* in the angle bar notches with which the rod is engaged. The retainer is held in position by the springs, the garment hangers are prevented from sliding forwardly, and the garments are 35 held from swinging back and forth on their hangers.

The retainer may readily be removed by 40 pressing down on the ends of bar *r* to release rod *t* from notches *w*, moving the bar *r* forward, one end at a time, until the ends of rod *t* clear the notched angle bars *v*, releasing bar *r*, and lifting the hanger *h* out of engagement with the supporter.

Having now fully described my invention, 45 what I claim and desire to protect by Letters Patent is:

1. In a wardrobe trunk, the combination with one of the trunk compartments, of a hanger supporter comprising members 50 slidable one upon another and provided with holes, of a hanger, a pin on the hanger adapted to engage said holes and thereby hold the hanger in fixed relation with the supporter, and a garment retainer depending from the hanger.

2. In a wardrobe trunk, the combination with one of the compartments of a trunk and garment suspending means positioned therein, of holding means secured to the trunk beneath the garment suspending means, and a garment retainer comprising a flexible body presenting a substantially continuous surface extending transversely across the greater part of the width of the 60 trunk and extending vertically from the gar-

ment suspending means to below the level of said holding means and a tension contrivance secured to the flexible body and adapted for engagement with said holding means.

3. In a wardrobe trunk, the combination with one of the compartments, of a trunk, of garment supporting means positioned therein, holding means secured to the trunk beneath said supporting means, a garment retainer comprising a flexible body and a tension contrivance, said tension contrivance comprising two cross-bars and springs connecting said bars independently of said flexible body, one of said bars being secured to 75 the flexible body, and means carried by the other bar adapted for engagement with the holding means.

4. In a wardrobe trunk, the combination with one of the compartments of a trunk, of garment supporting means positioned therein, a garment retainer comprising a flexible body and a tension contrivance, means for suspending the retainer at the upper part of the trunk compartment, and means to hold the lower end of the retainer in place, the flexible body extending down over the tension contrivance.

5. In a wardrobe trunk, the combination with one of the compartments of a trunk, of a hanger supporter therein, removable hangers on the supporter, a garment retainer adapted to extend down in front of any garments suspended from the other hangers, and holding means secured to the trunk beneath the supporter; said garment retainer comprising a flexible body secured to the front hanger, a rigid element engageable with the holding means and springs between the flexible body and the rigid element.

6. In a wardrobe trunk, the combination with one of the compartments of a trunk, of a hanger supporter therein, removable hangers on the supporter, a garment retainer secured to the front hanger and 110 adapted to extend down in front of any garments suspended from the other hangers, and complementary securing means on the front hanger and the supporter to position the front hanger fixedly at different points 115 on the supporter.

7. In a wardrobe trunk, the combination with one of the compartments of a trunk, of a hanger supporter positioned therein, a hanger adjustable on the garment supporter, holding means secured to the trunk beneath the supporter; and a garment retainer comprising a flexible body presenting a substantially continuous surface and supported from said hanger, and a tension contrivance secured to the flexible body and adapted for engagement with the holding means.

8. In a wardrobe trunk, the combination with one of the compartments of a trunk, of a hanger supporter therein, removable 130

hangers on the supporter, holding means secured to the trunk beneath the supporter, complementary securing means on the front hanger and the supporter to position the front hanger fixedly at different points on the supporter, and a garment retainer secured to the front hanger and adapted to extend down in front of any garments suspended from the other hangers and secured to said holding means.

9. In a trunk, a pair of rods secured to the upper portion thereof, telescopic sleeves over said rods, a plurality of hangers and a follower supported by said rods, a dust curtain suspended from said follower, a cross member adjustably supported in said trunk below said dust curtain, and spring connections between said member and said dust curtain for holding said dust curtain in position.

10. In a trunk, a pair of rods mounted in the upper portion of said trunk, hangers mounted upon said rods, a follower mounted upon said rods for holding said hangers in position, a series of holes in said rods, pins projecting downward from said follower for engaging with said holes for holding said follower in position, and a dust curtain suspended from said follower for holding the

garments in place and for protecting the same.

11. In a trunk, a pair of rods mounted in the upper portion of said trunk, hangers mounted upon said rods, a follower mounted upon said rods for holding said hangers in position, a series of holes in said rods, pins projecting downward from said follower for engaging with said holes for holding said follower in position, a dust curtain suspended from said follower for holding the garments in place and for protecting the same, a cross member adjustably mounted in said trunk below said dust curtain, and tension springs connecting said dust curtain to said cross member.

12. In a trunk, a pair of rods mounted in the upper portion of said trunk, hangers mounted on said rods, a follower mounted upon said rods for holding said hangers in position, a series of holes in said rods, and pins projecting downwardly from said follower for engaging said holes for holding said follower in position.

In testimony of which invention, I have hereunto set my hand, at Chicago, Illinois, on this 22nd day of January, 1919.

GEORGE F. GRUBE.
